AUDIBLE ELECTRIC SIGNALING
MECHANISMChristian Miller, Norwalk, Conn., assignor to
Edwards and Company, Inc., Norwalk, Conn.,
a corporation of New York

Application December 21, 1945, Serial No. 636,480

8 Claims. (Cl. 177—7)

1

This invention relates to audible electric signalling mechanisms, and more particularly to electrically actuated bells and buzzers.

One of the objects of this invention is to provide a dependable audible signalling device, electrically actuated, that will be of simple, compact, and economical construction and well adapted to meet varying requirements of practical use. Another object is to provide an electric signalling device, the individual parts of which will be simple and inexpensive, easy to fabricate, and easy to assemble. Another object is to provide an electric bell construction utilizing a gong element, with the actuating mechanism and gong element so constructed that the former will be efficiently housed within the latter and yet have a construction and action that will efficiently and effectively set the gong element into vibration for sound production when struck. Another object is to provide a mechanism and assembly therefor capable of complete or substantially complete accommodation within the gong element so that the latter serves as at least a part of the housing or enclosure.

Another object is to provide a combined bell and buzzer construction in which selection of bell action or buzzer action may be effected in a practical, reliable, and foolproof manner. Another object is to provide a signalling construction that can be quickly altered, and at will, to give a buzzer type of audible signal or a bell or musical tone type of signal.

Another object is, in general, to provide an improved construction and action for electrically-actuated, audible signalling devices, and other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawing, in which is shown, illustratively, a preferred form of the various possible embodiments of my invention,

Fig. 1 is a top or plan view of the complete device, certain parts being broken away;

Fig. 2 is a top or plan view of the device of Fig. 1, but with the gong element removed so as to show the internal parts;

Fig. 3 is a side elevation of the device;

Fig. 4 is a transverse cross-sectional view as seen along the line 4—4 of Fig. 1, certain of the parts there shown being also parts as seen along the line 4—4 of Fig. 2;

2

Fig. 5 is a plan view of the frame showing certain parts in development;

Fig. 6 is an elevation on a larger scale of an armature-striker unit at one stage of its construction; and

Fig. 7 is an enlarged perspective view of a contact unit.

Similar reference characters refer to similar parts throughout the several views of the drawing.

10 Referring, first, to Figs. 1 and 3, I provide a frame element 10 which is preferably round where the gong or bell element 11 is round. The frame 10 is preferably made of sheet metal and has a reinforcing side flange 12, the edge of which can 15 rest against the wall or surface to which the construction is to be secured, and an inwardly-directed flange 13 which may be given an upward and inward inclination, terminating, as along the line 14, in a circle of substantially the same diameter as the side wall 11^a of the gong 11, which 20 preferably has a top wall 11^b that has a central portion substantially flat or plane and preferably of considerable radius or area, for a purpose later described. The inwardly-directed flange 13 provides 25 a convenient area throughout which to distribute suitable holes for securing devices, such as screws or the like, and two such holes 15 and 16 are shown in Figs. 1 and 2. Within the area of the flange 13 I may also provide suitable connecting elements, such as binding posts or screws, 30 by which the external circuit conductors may be connected to the device, and two such binding posts are shown at 17 and 18.

The dome-like gong element 11 with the frame 35 10 can thus be given a neat and compact appearance, and, within the space underneath the gong 11, I accommodate an electrically-actuated striking mechanism constructed so as to give an effective whipping-striking action upon the gong, even 40 though it is accommodated within the small and restricted space underneath the gong, the latter, illustratively, having a diameter as small as two and a half inches or so. This mechanism comprises an electro-magnet, generally indicated by 45 the reference character 20, having a magnetic core 21 carrying end insulating disks 22 and 23 between which and about the core is the winding 24, one terminal of which is connected by conductor 25 to binding post 17, a conductor 26 50 leading from the other binding post 18 to complete the circuit through an interrupter device later described. The binding posts 17 and 18 are suitably insulated from the metal of the frame 10 in any suitable way, as by an internal strip of insulating material 27 (Fig. 4) and an external strip of insulating material 28 (Fig. 1). If de-

sired, where the frame part 13 slants upwardly and inwardly, those portions thereof that have the screw holes 15 and 16 and the binding posts 17 and 18 may be pressed or drawn downwardly into a horizontal plane, as indicated at 29, for the screw hole 15, and at 30, for the other screw hole and the binding posts 17 and 18 and their insulating strips 27 and 28; these parts, by such depression of the sheet metal, and the heads of the securing screws can thus be made more unobtrusive in appearance. If desired, the holes 31 and 32 (Figs. 1 and 2) may be provided to either side of the screw hole 16 so that, if the circuit conductors are not in the nature of surface wiring, but emerge, for example, from a recess, conduit hole, or the like in the wall over which the frame 10 is mounted, they can be brought out through the holes 31 and 32 and secured to the external portions or screws of the binding posts 17 and 18.

The frame 10 is preferably stamped and drawn out of a disk-like piece of sheet metal so as to provide an internal area or portion of sheet metal, indicated at 34 in Figs. 2, 3, and 5, the portion 34 being thus bridged across and supported by the frame 10, and with this arrangement it is thus possible, if desired, to make the portion 34 and certain other mounting parts formed out of it, as later described, integral with the frame 10. For example, out of the portion 34 there is cut or stamped a lug or bracket part 35 (Fig. 5) having a hole 36 therein and bent upwardly about the line 37 so that it stands upright, as shown in Fig. 2, a reduced end portion of the core 21 being received in the hole 36 and headed over, as at 21a, thus supporting the magnet 20 with its axis—in the illustration, substantially parallel to or coincident with a diameter of the frame or bridge portion 34.

In much the same manner a part 39 (Figs. 5 and 2) is cut out of the portion 34 and bent upwardly to form a post by which the armature and striker unit, generally indicated by the reference character 40, in Fig. 6, is mounted and supported for coaction, respectively, with the electro-magnet 20 and the gong 11. The unit 40 comprises an armature 41 and a striker 42 which extend substantially at right angles to each other, being preferably made out of a single stamping of suitably heavy steel in the shape shown in Fig. 6, the parts 42 and 41 being in the same plane as they are stamped out of the blank sheet metal and extending parallel to each other, having conformations, as indicated, to lessen waste in stamping a succession of them out of strip stock. The striker 42 can terminate in an enlargement which can be provided with a striker head 42a (Figs. 1 and 2), as by deformation of the metal or securing a separate part thereto. The striker arm 42 is then bent at right angles to the armature part 41, and to the latter is secured, as by rivets 43, a flat spring 44, shaped as shown in Figs. 6 and 2, having a mounting portion 44a by which it is secured, as by rivets 45, flatwise against the flat upstanding post 39 at a height (see Fig. 4) to bring the left-hand end of the armature portion 41 into juxtaposition to the end of the core 21 of the electro-magnet 20; the mounting spring 44 has a portion 44b that extends along one face of the armature 41, being bent away from the armature 41 somewhat, as shown in Fig. 2, and it is to serve as one of the contacts of the circuit making and breaking mechanism that is in circuit with the winding 24.

The companion part of the make and break mechanism comprises an upstanding post 46, con-

structed preferably in the manner shown in Fig. 7, having a horizontal base part 47 that has two downwardly-directed securing ears 47a and 47b which pass through two spaced slots in an insulating block 48, the ears being bent over against the underside of the block 48 so that the parts 46 and 48 form a single unit. In two opposed ends of the block 48 are formed recesses 48a and 48b which coact with securing ears 34a and 34b 10 provided in the bridging portion 34, as by cutting or stamping the latter along the broken lines 49 of Fig. 5. The unit 46-48, as seen in Fig. 7, and after the securing ears 34a and 34b have been bent upwardly, as viewed in Figs. 2 and 5, is placed in 15 position upon the upper face of the portion 34, the size of the insulating block being greater than the hole cut out along the lines 49 of Fig. 5, whence the upstanding lugs or ears 34a and 34b are received in the recesses or cutouts 48a and 48b of the insulating block 48 and are then bent over inwardly toward each other to anchor the unit 46-48 in position. The bent-over ends of the ears 47a and 47b are thus held out of engagement with the metal of the portion 34, and 20 the post 46 is thus maintained insulated from the portion 34 and the frame. One of the insulated conductors, such as conductor 26 that leads to the binding post 18, is connected to the contact post 46 in any suitable way, and, for example, may 25 have some of its insulation stripped off at an end and the bared conductor clamped inbetween the insulating block 48 and the base 47 of the post 46. The latter is provided with any suitable contact element to coact with the spring 44b, and such a 30 contact element may take the form of a screw 52 tightly threaded through a hole in the post 46. Thereby the coaction with the vibratable armature contact spring 44b may be adjusted, or the 35 post 46 may be bent for purposes of adjustment. 40 If a contact screw 52 is employed, its tightness of fit in the post 46 can suffice to retain it in adjusted position.

With one of the terminals of winding 24 connected to a binding post 17 by conductor 25, the other terminal can be grounded, for example, to the core 21, which, through its mounting 35, is grounded to the bridging part 34; likewise, the contact spring 44b is grounded by its connection to the post 39, and, with the contact post 46 insulated and connected by insulated conductor 26 to the binding post 18, the energization of the winding 24 is interrupted by the vibration of the armature 41 which on alternate strokes makes and breaks the energizing circuit contact 52 and spring 44b. The striker head 42a is thus likewise vibrated or oscillated, but at a multiplied amplitude, due to the relationship of the lengths of the lever arms, respectively, of the armature 41 and the striker arm 42 in relation to the effective axis 45 of pivoting which is in the spring 44 closely adjacent the apex of the angle between the parts 41 and 42. In relationship, however, to the circular cross-section of the depending side wall 11a of the gong 11, the moving strokes of the striker head 42a are in a direction at an acute angle thereto and, hence, most effective impacting of the gong to set it into sound-emitting vibration would not take place. Accordingly, I deform the side wall 11a of the gong 11 at a suitable point 50 therein, as at A, in Fig. 3, so as to provide an anvil, the face of which against which the striker head 42a is to impact extends substantially at right angles to the direction of the moving strokes of the striker head 42a. This I prefer to do by stamping or pressing a short peripheral portion of the

side wall 11^a inwardly, forming in effect an external notch in the gong 11 and having two wall portions 11^c and 11^e extending at substantially right angles to each other, with one of them, the portion 11^c , extending substantially parallel to the striker arm 42 and, hence, at right angles to the moving strokes of the striker head 42^a —all as is better shown in Fig. 1. The gong 11 is preferably a metal stamping of suitable heavy sheet metal of appropriate composition, and the external notch or deformation can be easily effected by a simple punch-press operation.

I, therefore, provide suitable means for quickly and simply determining the rotary position of the gong 11 and prefer to do this in a manner so that, optionally, the gong 11 may be set so that the reciprocating striker head 42^a strikes the anvil portion 11^c of the gong 11 when the effect or musical tone of the gong or bell is desired, or to hold the anvil portion 11^c out of striking range by the striker head 42^a when it is desired that the device function as a buzzer. A preferred manner of carrying this out comprises a suitable mounting, generally indicated by the reference character 55 , for supporting the gong 11 from the underside of its top wall 11^b and for selective rotary movement, as by a suitable pivotal connection, between the gong 11 and the mounting 55 ; such a pivotal connection may comprise a bolt, or screw, or rivet 56 passing through a hole, preferably at the center of the gong 11 , and into or through the mounting 55 , the clamping action being preferably yieldable so that the gong 11 may be given a rotary movement by hand relative to the mounting 55 and, hence, I prefer to include a spring washer 57 underneath the head of the member 56 . The spring washer 57 can thus interpose sufficient friction or give the pivotal mounting a spring-tightening in axial direction which can hold the gong against inadvertent rotary movement, but which can be overcome manually to give the gong the desired rotary shift.

Preferably I provide suitable means to limit the possible rotary movement of the gong, particularly to determine the proper positioning of the anvil 11^c when it is desired to have the device function as a bell. Such means may comprise an arcuate slot 11^f (Fig. 1) in the top wall of the gong 11 and positioned preferably at a substantial radial distance from its center which is coincident with the axis of pivoting provided by the pivotal connection 56 , and I provide in the mounting 55 an upstanding pin or projection 58 that projects into the slot 11^f . Accordingly, if the gong 11 is given a counter-clockwise rotary movement in Fig. 1, the anvil 11^c is swung away from the striker 42^a to bring it out of its range by an amount of rotary movement determined by the length of the slot 11^f , the right-hand end of which, when it engages the pin or stud 58 , limits such movement. Thereafter energization of the electro-magnet sets the armature-striker unit 40 into vibration, giving a buzzing sound, the gong not being set into vibration. If, however, a musical note of the gong is desired, the gong 11 is swung into clockwise direction and, hence, into the position shown in Fig. 1, where the left-hand end of the slot 11^f and the pin 58 , when in engagement, so limit the approach, toward the left, of the anvil 11^c to the striker 42^a that the subsequent reciprocation of the striker properly strikes the anvil 11^c and sets the gong into vibration. The slot 11^f can be of short length, in which case its substantial radial dis-

tance from the axis of the pivotal mounting of the gong insures precision of setting of the anvil 11^c for being struck by the striker 42^a .

Preferably I also provide suitable indexing means, aside from or in addition to the holding action of the spring washer 57 , for releasably holding the gong in each of its two above-described positions. In the underface of the top wall 11^b I provide two recesses or depressions 61 and 62 spaced apart by the same angle as is the permissible angle of rotary movement of the gong under the control of the pin 58 and slot 11^f , and projecting upwardly from the mounting 55 is a projection 63 formed as by deformation of the sheet metal of the mounting 55 and shaped so as to seat itself in either of the recesses 61 , 62 , to provide what may be called a hill-and-valley indexing means. The parts are preferably so related as to permit yielding movement away from each other of the gong and the projection 63 , as by a spring action, so that the projection 63 may be brought out of seating or interlocking relation with one of the recesses or seats 61 , 62 , and, when the other recess is brought around to the projection 63 upon rotary movement of the gong, the spring action effects seating or interlocking therebetween. This may be accomplished by the spring action of the spring washer 57 , which permits upward or tilting movement of the gong 11 to a sufficient extent, or by providing the projection 63 in a downwardly yieldable or resilient part of the mounting 55 , or both. The projection 63 can thus coact to yieldingly lock the gong 11 in either of the positions which it may take under the control of the pin 58 and slot 11^f , thus making sure that the vibration of the electro-magnetic mechanism, particularly during the bell action and the impacts upon the gong, does not effect rotary creeping of the gong out of its intended position.

The mounting 55 preferably comprises at least one, and preferably two, bracket-like supporting elements cut and bent out of the material of the sheet-metal portion 34 , and, where two such members are provided, they preferably coact to form a bridge-like bracket to support the gong, at its pivotal connection, at its center. In Fig. 5 one such bracket-forming member is shown in full outline at 65 , the full lines showing the lines along which the sheet metal of portion 34 is cut, and the broken line 66 showing the line along which the member 65 is bent upwardly out of the plane of the part 34 . In Figs. 2 and 4 the actual bend is also shown at 66 . From the bend 66 the bracket part 65 slopes upwardly and inwardly to one side of the striker arm 42 , whence it is bent, as at 67 , to provide a horizontal support portion 68 , which has a hole 69 therein for receiving the pivotal connecting element 56 . The part 68 provides a substantial flat area to engage against the under flat surface of the top wall 11^b of the gong, and at a free corner thereof (see Figs. 5 and 2) the projection 63 is provided, as by deforming the sheet metal upwardly, for selective coaction with the downwardly-exposed recesses 61 and 62 in the underface of the gong. The part 63 being located in a corner portion of the part 68 , the corner portion can yield due to the springiness of the sheet metal thereof, or the sheet metal may be slit, as along the line 70 , in Fig. 5, to form an elongated spring tongue 68^a to give the mounting of the projection 63 greater resiliency or springy action for snapping into either of the sockets or recesses 61 or 62 to form a re-

leasable lock and for yielding out of either of these recesses when sufficient torque is manually applied to the gong 11 to turn it.

As above indicated, I may, however, form and cut out of the sheet-metal portion 34 (Fig. 5) another bracket-like element, as indicated at 71, cutting it out along the full lines there indicated and bending it upwardly at an appropriate inclination (see Fig. 4) about the broken line 72, whence it is again bent, as at 73, to bring the end portion 74 into coaction with the flat portion 68 of the companion bracket element 65. These companion portions project toward each other (Fig. 5) so that when each of the bracket elements is bent, as above described, parts of the portions 68 and 74 are brought into overlapping relation (see Figs. 2 and 4), and the hole 75 in the one and the hole 69 in the other are brought into registry to receive the gong pivoting element 56 which may, thus, also serve to connect the two parts 68 and 74 mechanically together. If desired, and preferably, the underlapping part 64 may be conformed or bent, as shown in Fig. 4, so that the upper face of the rest of it is in the same plane with the upper face of the part 68, thus to provide a large, flat surface against which the top wall of the gong may rest and symmetrically disposed, for balanced support of the gong, with respect to the axis of pivoting of the gong. The bracket parts 11 and 65 (Figs. 4 and 2) thus complement each other and together they form a gong-supporting bridge that extends over the electro-magnetic actuating mechanism.

If desired, suitable indicia coacting with the gong 11 may be provided to indicate the setting of the gong for either bell or buzzer action. For example, adjacent the one end of the slot 11^f there may be applied, as by stamping, indicia such as "Be," and adjacent the other end the designation "Bz" can be applied, to indicate that when the parts are set so that the visible stud or projection 58 is at the "Be" end of the slot, the parts are set for bell action, and, to set them for buzzer action, adjustment is made to bring the "Bz" end of the slot and the projection 58 together.

It will thus be seen that there has been provided in this invention an electrically actuated, audible signalling apparatus in which the various objects above noted, together with many thoroughly practical advantages, are successfully achieved. It will be seen that the construction is of a thoroughly practical nature, is economical to manufacture, and is of thoroughly reliable and flexible or selectable action in practical use.

As many possible embodiments may be made of the above invention and as many changes might be made in the embodiment above set forth, it is to be understood that all matter hereinbefore set forth, or shown in the accompanying drawing, is to be interpreted as illustrative and not in a limiting sense.

I claim:

1. A signalling construction comprising a frame element having a gong supporting bracket, a gong closing over the frame and supported pivotally by said bracket, electro-magnetically-actuated striker mechanism accommodated in the space underneath the gong and having a striker for striking a portion of the gong, means interrelating the path of striking movement of the striker and said gong portion whereby operative gong-striking action is dependent upon the position of the gong about the axis of its pivotal connection to the bracket, whereby said gong may

be moved in one direction about its pivot so that said gong portion is out of the range of striking movement of the striker and the apparatus produces an audible buzzing signal, and means for determining pivotal movement of the gong in opposite direction to position said gong portion suitably with respect to the striker movement of the striker so that the apparatus produces an audible gong signal, said gong having a dome-like shape of generally circular cross-section and its axis of pivoting being substantially at its center, said gong presenting an internal surface with respect to which the moving strokes of the striker are at substantially an acute angle, said gong portion comprising means projecting inwardly from the gong at substantially a right angle to the striking movement of the striker, whereby upon pivotal movement of the gong said means moves in a peripheral direction into or out of operative relation to the striker.

2. A signalling construction comprising a frame having a sheet-metal gong supporting bracket, a gong overlying said bracket and frame and having a pivotal connection with the bracket for rotary movement of the gong about the axis of the pivotal connection, and electro-magnetic striker mechanism mounted underneath the gong and having a striker for striking the gong, said gong having anvil means movable, upon rotary movement of the gong, into or out of operative striking relation to the striker, whereby the apparatus may be set for gong-striking action or for buzzer action.

3. A construction as claimed in claim 2 in which said gong and bracket have coacting pin-and-slot means to limit rotary positioning of the gong for gong action or buzzer action.

4. A construction as claimed in claim 2 in which said pivotal connection comprises means for frictionally holding the gong from movement out of either of its rotated positions when set for gong action or buzzer action.

5. A construction as claimed in claim 2 in which said gong and said bracket have coacting disengageable indexing means for releasably holding the gong against undesired rotary movement out of position.

6. A construction as claimed in claim 2 in which said sheet-metal bracket has a resilient portion movable toward or away from the gong, said resilient portion and said gong having coacting hill-and-valley indexing means for interengagement releasably under the yielding action of said resilient portion.

7. An electric bell construction comprising a sheet-metal frame having a portion thereof struck therefrom and bent upwardly into overlying relation thereto to form a gong supporting bracket, a dome-like gong supported by said bracket and overlying said frame to form a casting-like enclosure therewith, an electro-magnetic winding having a bracket-like support therefor formed by striking and bending out of a portion of the sheet metal of the frame for supporting the winding underneath the dome, and striker means responsive to said electro-magnetic winding and striking said gong internally thereof.

8. An electric bell construction comprising a dome-like gong, a sheet-metal frame-like base having struck out of the sheet metal thereof underlying the gong a plurality of parts that are bent upwardly and meet substantially above the center of the base to form a composite bracket support for the gong, means for securing the gong to said parts of the composite bracket, and

9

electro-magnetic means underlying said composite bracket support and including striker means actuated thereby for impacting the gong.
